UNITED STATES PATENT OFFICE

139,711

DESIGN FOR AN INFANT'S COMMODE

John Pannhausen, Oak Park, and Carl A. Raabe,
Chicago, Ill.

Application September 18, 1944, Serial No. 115,364

Term of patent 14 years

(Cl. D4—5)

To all whom it may concern:

Be it known that we, John Pannhausen and Carl A. Raabe, citizens of the United States, residing in the county of Cook and State of Illinois, have invented a new and original and ornamental Design for an Infant's Commode, of which the following is a specification, reference being had to the accompanying drawing, forming a part thereof.

In the drawing,

Fig. 1, showing our new design, is a top view of the infant's commode;

Fig. 2 is a side elevational view thereof;

Fig. 3 is a sectional view on line 3—3 as shown in Fig. 2.

We claim:

The ornamental design for an infant's commode, as shown.

JOHN PANNHAUSEN.
CARL A. RAABE.
